UNITED STATES PATENT OFFICE.

OSKAR OLSEN PANENGEN, OF SKREIA, NORWAY.

FLAT TILE.

1,249,662.

Specification of Letters Patent. Patented Dec. 11, 1917.

Application filed December 6, 1915. Serial No. 65,308.

To all whom it may concern:

Be it known that I, OSKAR O. PANENGEN, residing at Skreia in Norway, a subject of the King of Norway, have invented certain 5 new and useful Improvements in Flat Tiles, of which the following is a specification.

My invention relates to improvements in flat tiles, the object being to provide means whereby the tiles may be made very thin and 10 yet be strong.

Figure 1 is a side-view and Fig. 2 bottom-view of a square tile, Fig. 3 is a portion of a roof covered with such tiles, Figs. 4 and 15 5 is side-view and bottom-view respectively of an oval or oblong tile.

With reference to Figs. 1, 2 and 3 the body 1 of the tile on its underside is provided with a rib 2 placed along the edges of the tile. On the place where the tile is resting on the 20 purlin (shown in dotted lines) the rib is cut away. The rib-portions 3 and 4 next to the top corner will then serve as a button or hook for engagement with the purlin. The rib-portions 5 and 6 next to the bottom corner are drawn back a suitable distance from the edges of the tile-body according to the 25 desired overlapping of the underlying tiles. On the place facing the purlin the tile is provided with a filling 7 so as to produce a good bearing surface. The side corners of 30 the tile-body are cut away to form contact surfaces 8, 8 for the adjoining tiles in the same horizontal row.

The rib 2 has the principal object to 35 strengthen the tile against breakage but it

is also of use during transport, as otherwise the button would be in the way during packing and then the lower rib portions 5 and 6 will steady the tile by being in contact with the edges 9 and 10 of the underlying tiles. 40

In order to further strengthen the tile I may provide a central rib 12.

The tile shown in Figs. 4 and 5 is an imitation of the slate-tiles. The tile body 13 is provided with a rib 14, 15 and button 16 45 at the top and also filling 17 forming bearing surface for the purlin (in dotted lines). The upper part of the tile has incurved edge portions 18 and 19, the curvature of said portions corresponding to the curvature of 50 the rib portions 14 and 15 respectively, so that in position on the roof said rib-portions are in contact with the curved edge portions 18 and 19, whereby the position of the tile is steadied. 55

What I claim as my invention is,—

A tile being formed adjacent its edges with ribs, said ribs being interrupted through a certain portion of their length wherein to accommodate the purlin, such space sloping 60 upwardly toward the end of the tile in order to obtain a good contact surface against such purlin.

In testimony whereof I affix my signature in presence of two witnesses.

OSKAR OLSEN PANENGEN.
